UNITED STATES PATENT OFFICE.

CHARLES MEHLHORN, OF PHILADELPHIA, PENNSYLVANIA.

ROADWAY.

1,271,921.

Specification of Letters Patent.

Patented July 9, 1918.

Application filed March 12, 1918. Serial No. 222,005.

To all whom it may concern:

Be it known that I, CHARLES MEHLHORN, a citizen of the United States, residing at Philadelphia, in the county of Philadelphia and State of Pennsylvania, have invented 5 certain new and useful Improvements in Roadways, of which the following is a specification.

One object of my invention is to provide 10 a roadway which will withstand heavy traffic without becoming irregular on its surface.

Another object is to so construct my improved roadway that it can be quickly made 15 and at a comparatively low cost.

These objects, and other advantageous ends which will be described hereinafter, I attain in the following manner, reference being had to the accompanying drawings in 20 which—

Figure 1 is a fragmentary top plan view of a roadway made in accordance with my invention,

Fig. 2 is a sectional elevation taken on the 25 line 2—2 of Fig. 1;

Fig. 3 is a fragmentary top plan view of a rail which provides a wear surface for the roadway,

Fig. 4 is a side view of Fig. 3,

Fig. 5 is an inverted plan view of Fig. 3;

Fig. 6 is an enlarged fragmentary section taken on the line 6—6 of Fig. 1,

Figs. 7, 8, and 9 are views of similar nature to Fig. 2 showing different modifications of my invention, and

Fig. 10 is a fragmentary sectional view showing a modification of my invention.

Referring to Figs. 1 to 6, inclusive, of the drawing, 1 represents the bed of my improved roadway which is formed of concrete or concrete cement. Spaced apart and embedded within the bed 1 are the metallic rails 2 and 3 which are similarly constructed and have their upper surfaces 4 flush with 45 the top surface 5 of the bed 1. These rails have rough upper surfaces, the roughening of the surfaces, as shown at 2^a, preferably being formed by providing crossed ribs 3^a and recesses 4^a which can be produced while 50 the rails are being made by rolling the rails with rollers having recesses and ribs thereon. In the drawings this roughening is only illustrated on a portion of the upper surface, as shown in Figs. 1 and 3, so as not to obscure the other details of these views of drawing. The rails 2 and 3 are embedded

within the bed 1 while the latter is in a soft or plastic state and prior to the "setting" of the same. The rails 2 are preferably made in sectional lengths of any size which is convenient to handle and are made channel-shape in cross section with their sides 6 tapering downwardly, as clearly shown in Fig. 6, to provide undercut pockets 7 which are filled with the concrete or cement of the roadway and thereby anchor the rails within in the road bed.

As illustrated, I have provided additional anchoring means for the rails within bed 1 by respectively stamping and pressing 70 tongues 8 and 9 out of the opposite sides 6 and top of the rails.

The tongues 8 are hooked at their inner ends, as shown at 10, and pockets 11 (see particularly Fig. 5) are thus provided so 75 that a portion of the cement of the bed 1 is housed or confined in these pockets 11. Thus auxiliary means is provided to prevent any chance of lateral displacement of the rails. Furthermore, the tongues 8 are spaced below 80 the lower surface 12 of the top of the rails so that a portion of the cement of the bed 1 is interposed between the tops of the tongues 8 and the bottom surface 12 of the rails. Hence these tongues 8 also serve to prevent 85 the rails from rising away from the cement bed.

The tongues 9 extend downwardly into the bed 1 and have hooked ends 13, as clearly shown in Fig. 4. These hooked ends provide 90 pockets 13^a in which a portion of the cement of the bed 1 is confined, and additional means is thus provided to anchor the rails within the bed 1.

The tongues 8 and 9 are provided throughout the lengths of the rails and may be formed at any suitable distance apart according to requirements. The top surfaces 4 of the rails provide a track for vehicles and constitute wear surfaces for the cement 100 bed 1. The rails formed in accordance with the above description are capable of supporting great weight, such for example as heavy motor trucks or other vehicles which must necessarily run upon public roadways. 105 Furthermore, the rails 4 are made comparatively wide so that ordinary variation in the travel of a vehicle is possible without the vehicle running off the rails. Also since the tops of the rails are made flush with the 110 top of the bed 1, they can readily turn off of the track when desired without any ma-

terial jar to the vehicle or injury to the road bed.

The rails can be cheaply made, if desired, out of sheet metal which is rolled and punched to provide the tapered sides 6 and tongues 8 and 9.

In the form of my invention shown in Fig. 7, I have shown a cement or concrete bed 14 in which are embedded pedestals 15 which 10 may be made of wood or other suitable material. These pedestals flare downwardly and thereby are securely anchored within the bed 14. Rails 16 are provided and have rods or spikes 17 which secure them to the pedestals 15. In this instance also the tops of the rails are made flush with the top surface of the bed 14 and the rails and pedestals are securely embedded within the cement of the bed 14, while the latter is in 15 a plastic or soft condition and prior to the 20 "setting" of the same.

In the form illustrated in Fig. 8, the rails 18 are formed by embedding blocks 19 within cement bed 20, while the latter is in a 25 soft and plastic state. The tops of the rails are made flush with the top of the bed 20.

In Fig. 9 I have shown a construction which is substantially similar to the form of my invention illustrated in Figs. 1 to 6, 30 inclusive, with the exception that instead of making the entire bed of cement or concrete, I provide cement or concrete pedestals 21 which are spaced apart and the rails are embedded within these pedestals. The space 35 between the pedestals can be filled in with any other material desired, such for example as ordinary ground or earth. In all other respects the construction of the elements is similar to that described in connection with Figs. 1 to 6 inclusive, and I have 40 therefore given similar parts corresponding reference numerals.

In Fig. 10 I have shown a rail which, instead of being provided with tongues, as 45 above described, has spikes or bolts 23 inserted through the sides thereof and are provided with heads 24. I also insert spikes or bolts 25 downwardly from the top of the rail and provide these spikes with heads 26. 50 These spikes or bolts provide additional anchors for the rail within the concrete bed 27.

While I have described my invention as

taking a particular form, it will be understood that the various parts of my invention may be changed without departing from the spirit thereof, and hence I do not limit myself to the precise construction set forth, but consider that I am at liberty to make such changes and alterations as fairly 60 come within the scope of the appended claims.

Having thus described my invention, what I claim as new and desire to secure by Letters Patent is:

1. A roadway including a concrete bed; rails spaced apart and embedded within said bed, said rails having top portions flush with the top surface of the bed; and members spaced apart within the length of said rails, said members depending from said portions and being embedded within said concrete bed, substantially as described.

2. A roadway including a concrete bed; 75 and rails spaced apart and embedded within said bed, said rails having top portions flush with the top surface of the bed, each of said rails having side flanges tapering downwardly and toward each other, said side flanges being embedded within the concrete 80 bed, the space between said flanges and said top portions of the rail also being filled with concrete of the bed, substantially as described.

3. A roadway including a concrete bed; 85 and rails spaced apart and embedded within said bed, said rails having top surfaces flush with the top surface of the bed, said rails having tongues partly cut therefrom and embedded within said bed, substantially as 90 described.

4. A roadway including a concrete bed; 95 and rails spaced apart and embedded within said bed, said rails having top surfaces flush with the top surface of the bed, said rails having hooked tongues spaced apart within their lengths and embedded within said bed, substantially as described.

In testimony whereof I have signed my name to this specification in the presence of 100 two subscribing witnesses.

CHARLES MEHLHORN.
